COMBINED RAZOR AND SLIP CAP

Donald M. Genaro, Haworth, N.J., and Clemens A. Iten,
Staunton, Va., assignors to Philip Morris Incorporated,
New York, N.Y., a corporation of Virginia

Filed Oct. 9, 1969, Ser. No. 19,473

Term of patent 14 years

Int. Cl. D28—03

U.S. Cl. D95—3

FIG. 2

FIG. 3

FIG. 1 is an exploded perspective view of a combined razor and slip cap showing our new design;

FIG. 2 is an elevational view from the rear of FIG. 1, with the slip cap in place; and

FIG. 3 is a bottom plan view.

We claim:

The ornamental design for a combined razor and slip cap, as shown.
